UNITED STATES PATENT OFFICE.

GEORGE A. SAGER, OF ALBANY, NEW YORK.

SAFETY BOILER PLUG AND METHOD OF INSTALLING SAME.

Application filed August 19, 1920. Serial No. 404,659.

To all whom it may concern:

Be it known that I, GEORGE A. SAGER, citizen of the United States, residing at Albany, in the county of Albany and State of New York, have invented certain new and useful Improvements in Safety Boiler Plugs and Methods of Installing Same, of which the following is a specification.

This invention relates to an improved boiler plug and method of installing same and has as one of its principal objects to provide a plug which cannot blow out, which cannot be carelessly or dangerously inserted and which will accordingly, in practical use, prove absolutely safe.

A further object of the invention is to provide a plug which will project through the sheet of a boiler from the inner side of said sheet and wherein means will be provided for adjustably clamping the plug into engagement with its seat.

A still further object of the invention is to provide a plug wherein the clamping means therefor will be yieldably held against working loose and wherein said means will be so formed that destruction or mutilation of equipment will be prevented in tightening the clamping means.

And the invention has as a still further object to provide a construction wherein the plug will be anchored to the boiler sheet so that the plug cannot become accidentally lost or cannot fall into the boiler when the boiler is undergoing repairs.

Other and incidental objects will appear hereinafter.

In the drawings:

Figure 1 is a fragmentary front elevation of the back head of a locomotive boiler showing my improved plug in position thereon,

Figure 2 is a vertical sectional view more particularly illustrating the mounting of the plug,

Figure 3 is a detail elevation looking at the outer end of the plug,

Figure 4 is a detail elevation looking at the inner end of the plug,

Figure 5 is a detail perspective showing the clamping bolt for the plug,

Figure 6 is a fragmentary vertical section showing the manner in which the plug is installed, and

Figure 7 is a fragmentary vertical section illustrating a slight modification of the invention.

Referring now more particularly to the drawings, I have shown my improved plug in connection with the back head 10 of a locomotive boiler of conventional design. Spaced from the back head is the usual back sheet 11 and extending between said sheet and the head are the customary stay bolts 12. Entering through the back sheet is an arch tube 13. In this connection it is to be understood that my improved plug is applicable to any portion of a boiler shell or sheet where arch bar plugs or washout plugs are employed and I do not, therefore, wish to be limited in this regard. In carrying the invention into effect, I form through the back head opposite the arch tube, a circular opening 14 and at the inner end of this opening is provided a beveled seat 15. Removably fitted in the said opening from the inner side of the back head is a plug. This plug comprises an annular plug body 16 which is formed with a beveled annular seat 17 to rest flat against the seat 15 of the back head and extending from the plug body outwardly through the back head is a short shank 18. Rising from the inner or larger end of the plug axially thereof is a headed stud 19 and entering through the plug shank opposite said stud is, as particularly shown in Figure 3 of the drawings, an oblong slot 20. At the inner end of this slot, the side walls thereof are, throughout the major portion of their width, reversely undercut at opposite ends of the slot to provide, as shown in dotted lines in Figure 3, a recess 21 in the plug body standing at substantially a right angle to the slot.

Anchoring the plug to the back head is a short length of chain 22 extending at the inner side of said head. As particularly shown in Figure 4, the lowermost link of this chain is provided with a split loop engaging around the headed stud 19 of the plug to provide a swivel connection between the chain and the plug while, as shown in Figure 2, the uppermost link of said chain is engaged through the eye of an eye bolt or anchoring member 23. This eye bolt is formed with a longitudinally tapered shank 24 which projects outwardly through a reversely tapered opening in the back head 10 snugly fitting said opening, and securing the eye bolt to the back head is a weld 25 forming a head at the outer end of the shank coacting with the back head. As

particularly brought out in Figure 1, the eye bolt is preferably arranged directly above the plug while the chain 22 is of such length that, when the plug is displaced 5 from the opening 14 in the back head, the plug will be supported at the inner side of the back head opposite said opening so that said plug may be readily reached. By displacing the plug inwardly and then, with 10 a stick or tool inserted through the opening 14, throwing the plug over an adjacent one of the stay bolts 12, access may be readily had to the confronting end of the arch tube 13 for cleaning, rolling, or renewing said tube. As will be seen, the plug 15 is effectually secured to the back head so that the plug cannot be mislaid or lost while the boiler is undergoing repairs, nor can the plug fall downwardly into the boiler.

20 Normally securing the plug in position closing the opening 14 through the back head is a clamping bolt 26 which, as shown in detail in Figure 5, is provided with a T-head 27. This T-head is freely insertible 25 through the slot 20 of the plug shank when, by rotating the bolt a quarter turn, the head thereof will be caused to engage within the recess 21 of the plug. Freely surrounding the bolt shank to overlie the plug shank 30 is a resilient cupped washer 28 and threaded upon the shank to coact with said washer is a nut 29. Thus, this nut may be adjusted for tightly clamping the plug within the opening 14 of the back head and binding 35 the beveled seat 17 of the plug in engagement with the beveled seat 15 of said head to provide a closed joint therebetween. As the nut is adjusted, the washer 28 will, of course, be sprung or flexed somewhat so that 40 the washer will be caused to resiliently bind against the nut therebeneath for frictionally locking the nut in adjusted position. In this connection, attention is directed to the fact that, as particularly shown in Figure 45 2, the thread upon the bolt shank stops at its inner end in spaced relation to the end face of the shank of the plug and at such point that should the nut be adjusted inwardly until the washer is flexed into engagement with the plug shank, the nut will have then reached the inner end of the thread. Consequently, the nut cannot then be further adjusted inwardly to cause mutilation of the back head or plug. On the 50 other hand, after the nut has reached the inner end of its thread, further rotation of the nut will serve only to rotate the plug or twist the bolt off so that injury to the equipment will thus be effectually prevented. At its outer end the bolt shank is formed with a reduced apertured ear 55 through which may be engaged a wire or tool for holding the bolt while the washer 28 and nut 29 are assembled thereon.

60 65 In order that the device may be readily

installed, the shank of the eye bolt 23 is, as shown in Figure 6, originally formed with a threaded portion 31 provided at its outer end with an opening 32 and connected with the tapered portion of the shank by a reduced neck 33. A collar or spacer 34 is provided as is also a washer 35 adapted to rest against the collar while a nut 36 threaded to engage the threaded portion 31 of the eye bolt shank is also employed. In installing the device the eye bolt having the chain and plug attached thereto is lowered within the water space of the boiler at the rear of the back head until the eye bolt appears at the opening 14. A workman then 80 seizes the eye bolt when a length of wire is engaged through the opening 32 thereof and the free end of the wire directed outwardly through the eye bolt opening in the back head. By then pulling upon the wire the 85 shank of the eye bolt may be drawn through said opening, the bolt shank being preferably provided at its outer end with an arrow or other mark denoting the disposition of the eye at the inner end of the bolt so 90 that the bolt may be rotated and the eye readily disposed vertically. The spacer 34 is then arranged about the shank of the eye bolt and the washer positioned against said spacer when the nut 36 is applied to the 95 threaded portion 31 of said shank and adjusted inwardly thereon for forcibly drawing the tapered portion of the eye bolt shank outwardly through the opening in binding engagement with the 100 wall thereof to form a closed joint between the eye bolt and the back head. The nut, washer and spacer are then removed when the weld 25 is formed. This done, the threaded portion 31 of the shank of 105 the eye bolt is broken off at the neck 33. The eye bolt will then support the plug suspended opposite the opening 14 through the back head so that the clamping bolt 26 may be readily engaged with the plug for securing 110 the plug in place. In this connection, it is to be observed that the plug cannot, through carelessness, be secured within the plug opening of the back head in such manner that blowing out of the plug will result, 115 since the larger end of the plug being disposed at the inner side of the back head will overcome this contingency.

120 In Figure 7 of the drawings, I have illustrated a slight modification of the invention. In this figure, the back head is indicated at 37. Formed through this head is an opening 38 corresponding to the opening 14 as shown in connection with the preferred construction and provided at its inner end with a beveled seat 39. Removably fitted through the opening is a plug including an annular plug body 40 having a beveled seat 41 engaging the seat 39 of the back head. Rising from the inner end of the plug 125 130

is a headed stud 42 with which is freely engaged a chain 43 anchoring the plug as in the preferred construction. The modified form of plug is particularly intended for use 5 in any instance where the plug is too small to be cored out or recessed for receiving a clamping bolt as shown in connection with the preferred form of the invention. Instead, the plug is formed with an elongated 10 shank 44 through which is a diametric slot and removably fitting through said slot is a wedge shaped key 45. This key is secured against accidental loss by a length of chain 46 appropriately connected to the back head 15 and preferably, a washer 47 is disposed between the key and the back head for spacing the key therefrom. As will be seen, the key will serve to effectually secure the plug in place and by advancing the key 20 through the plug shank, the beveled seat 41 of the plug may be drawn into binding engagement with the beveled seat 39 of the back head to provide a sealed joint therebetween.

25 Having thus described the invention, what is claimed as new is:

1. The combination with a boiler sheet having a tapered opening therethrough and being provided with a second opening, of a 30 plug closing the latter opening from the inner side of the sheet, an anchoring member

having a tapered shank fitting through said opening from the inner side of said sheet, and connecting means between said member and the plug.

35

2. The combination with a boiler sheet having an opening therein, of a plug closing said opening from the inner side of the sheet and provided at its inner end with a stud, and means permanently anchoring the 40 plug to the sheet and having swiveled connection with said stud.

3. The combination with a boiler sheet having an opening therethrough, of a stationary anchoring member connected directly to the sheet and extending at the inner side thereof, a plug closing said opening from the inner side of the sheet, and flexible connecting means at the inner side 45 of the sheet between the plug and said member.

4. The combination with a boiler sheet having spaced openings therethrough, of an anchoring member fitting through one of said openings and extending at the inner 55 side of the sheet, a plug closing the other of said openings from the inner side of the sheet, and flexible connecting means at the inner side of the sheet extending between said member and the plug.

60

In testimony whereof I affix my signature.
GEORGE A. SAGER.
